(57) **CLAIM**

I claim the ornamental design for a receiver for tobacco smoker's waste, as shown and described.

DESCRIPTION

FIG. 1 is a perspective view of the invention with a portion of a container, to which it is removably attached, shown in broken lines.

FIG. 2 is a front elevation view of the invention;

FIG. 3 is a right side elevation view thereof;

FIG. 4 is a left side elevation view thereof;

FIG. 5 is a top plan view thereof;

FIG. 6 is a rear elevation view thereof; and,

FIG. 7 is a bottom plan view thereof.

The broken line disclosure of the container is shown for illustrative purposes only and forms no part of the claimed design.
